UNITED STATES PATENT OFFICE.

CHARLES E. NEEDHAM, OF ALLENTOWN, PENNSYLVANIA, ASSIGNOR TO BRADLEY PULVERIZER COMPANY, OF BOSTON, MASSACHUSETTS, A CORPORATION OF MAINE.

SHAFT-COUPING FOR GRINDING-MILLS.

1,095,986.

Specification of Letters Patent.

Patented May 5, 1914.

Application filed October 16, 1912. Serial No. 726,018.

To all whom it may concern:

Be it known that I, CHARLES E. NEEDHAM, a citizen of the United States, and resident of Allentown, county of Lehigh, State of Pennsylvania, have invented an Improvement in Shaft-Couplings for Grinding-Mills, of which the following description, in connection with the accompanying drawing, is a specification, like characters on the drawing representing like parts.

This invention relates to grinding or pulverizing mills wherein the material to be reduced is acted upon by a suspended revoluble roll having a gyratory action with relation to the suspension means therefor and which roll coöperates with an annular die, such a mill being shown in United States Patent No. 1,020,092 dated March 12, 1912. In mills of this type the driven or roll shaft is connected with an overhead and suitably supported driving shaft by a substantially universal coupling, comprising essentially a closed outer member fixedly attached to the driving shaft and provided with a belt pulley, and an inclosed coöperating rocking member or cross-head rotated bodily and positively in unison with the outer member, the roll shaft being attached fixedly to and depending from the cross-head. Such a coupling structure is shown in United States Patent No. 721,035 dated February 17, 1903, and in practice mills of the type referred to must be maintained thoroughly lubricated in all parts of the universal coupling, as from the nature of the case the moving parts of the mill are subjected to the most severe work. The oil is introduced into the closed outer member of the coupling in considerable quantity, but it must be renewed at frequent intervals for it is found in practice that the oil escapes very rapidly from the outer member of the universal coupling between the contacting surfaces of the coöperating suspension members 33, 37 of Patent No. 1,020,092 and flows down the roll shaft. This constant lubrication of the coupling and its adjuncts is very objectionable, because of the waste, and irregularity of lubrication, and the mixing of the waste lubricant with the material being ground.

My present invention has for its object the production, in a grinding mill of the type above referred to, of means for improving the lubrication of the parts, and pre-

venting the escape of the lubricant from the outer or inclosing member of the universal coupling, whereby the foregoing objections are obviated.

By the present invention I am also enabled to provide for the reception and storage of a relatively large quantity of lubricant, so that enough for a long run of the mill can be introduced into the coupling whenever it is necessary to replenish the supply.

The various novel features of my invention will be fully described in the subjoined specification and particularly pointed out in the following claims.

Figure 1 is a view in elevation and section of a sufficient portion of a grinding mill of the type referred to, with one practical form of my present invention embodied therein; Fig. 2 is an enlarged view, mainly in diametral section, of the cross-head, the coöperating thrust members, and the means for retaining lubricant in the pulley or outer member of the universal coupling which connects the driving shaft and the roll-shaft of the mill.

Referring to Fig. 1, the frames 1 which carry the annular concave seat 2 for the bearing 3, the cross-piece 4 supported by the upright frame members 5 and sustaining the seat 6 for the bearing 7 of the depending driving shaft 8, the hub 9 of the driving pulley 10, in which hub the lower end of said shaft is secured, the cylindrical bottom portion 11 bolted to and depending from the pulley hub and terminating in a flared tubular extension 12 onto which the bearing 3 is clamped, said bottom portion 11 having an internal annular shoulder 13, and the concaved bearing ring 14 seated on such shoulder, to take up the end thrust transmitted by the roll-shaft, may be and are all substantially as in United States Patent No. 1,020,092 dated March 12, 1912, except in such particulars as will be pointed out hereinafter. The pulley hub 9 and the attached depending portion 11 constitutes an inclosed outer or socket member of the universal coupling which connects the driving or suspending shaft 8 and the suspended, driven roll-shaft 15, which in practice carries at its lower end the grinding roll, of well known construction. Within the socket member are diametrically disposed and upright concaved seats 16, each usually made

in two parts for convenience, as shown, and coöperating with the convex end faces of segments 17 centrally apertured to fit easily upon oppositely extended trunnions 18 which project radially from a cross-head 19. Herein I have shown the cross-head as extended some distance above and below the trunnions, the upper part having a tapered axial hole 20, Fig. 2, to receive the correspondingly tapered end 21 of the roll-shaft 15, which latter is locked in the cross-head in any suitable manner, as by a transverse pin 22 projecting from opposite sides of the shaft and resting on oppositely inclined cam seats 23 on the cross-head, one of such seats being shown herein. No claim is made herein to such locking device, as the same is not of my invention. The lower part of the cross-head has a tapered, frusto-conical recess 24 formed therein co-axial with and communicating with the hole 20, as clearly shown, but the taper of the recess is materially greater than that of the hole 20, and the recess is much larger in diameter. The lower end of the cross-head is shaped to present an internal annular seat 25 within the lower end or mouth of the recess 24, as shown, to receive an annular neck 26 formed on the suspension member 27, made as a spherical segment and seated in the concaved bearing 14 hereinbefore referred to. As will be apparent the weight of the roll shaft, roll and cross-head is sustained by the said segment 27, which is made of manganese steel or other suitable wear-resisting material, and by the construction referred to above it interlocks with the cross-head under normal working conditions, the annular bottom 28 of the cross-head seating upon the flat top face 29 of the segment surrounding the neck 26. The interlocking of the segment and cross-head prevents any relative lateral movement of such parts, and this is important in my present invention, for the tapered central shaft aperture 30 of the segment or suspension member 27 is thereby maintained co-axial with and a continuation of the recess 24 of the cross-head. Consequently, while the suspension member can be readily renewed when necessary it moves with the cross-head as if it were a unitary part thereof under working conditions. In prior structures of this type the main body of oil introduced into the inclosing or outer member 9, 11 of the coupling by the central hole 8* in the driving shaft 8, Fig. 1, and such oil as passes through the ducts 31 from the chamber 32, has escaped rapidly by passing between the opposed surfaces of the co-operating suspension members 14 and 27, it being understood that the gyratory movement of the roll shaft is continuous while the mill is in operation, and as pointed out previously the waste of oil, the irregular lubrication, and the frequent renewals of oil

are highly objectionable. In the present embodiment of my invention I obviate the objections noted by attaching in an oil tight manner to the tubular extension 12 an oil guard or retainer, shown as a tubular frusto-conical member 33, preferably made of cast brass or other suitable metal and having at its lower end a relatively heavy lateral, annular flange 34 which enters in an annular seat 35 formed in the interior of the extension 12 inside the shoulder 13 thereof. The seat has a cylindrical side wall and the bottom is at right angles thereto, as clearly shown in Fig. 2, and the flange 34 is shaped to fit very accurately in the seat, and in practice the diameter of the flange is made slightly larger than the diameter of the seat, so that the flange of the retainer is forced by heavy pressure into the seat. This makes an absolutely fluid-tight and rigid joint between the retainer or guard 33 and the bottom portion of the outer member of the coupling, as will be obvious, the retainer being coaxial with the said coupling member and it is shown as projecting upward thereinto substantially to the plane of the joint between the hub part 9 and cylindrical bottom part 11 of the coupling member, see Fig. 1. Said oil retainer enters the recess 24 in the cross-head, and the roll shaft passes through the retainer, as shown in Fig. 1, the inclination of the wall of said retainer being such that the roll shaft will have ample room for its maximum gyratory movements, as shown in Fig. 1. So, too, the taper or inclination of the wall of the recess 24 is such that it will be clear of the oil retainer at all times and under all conditions of gyratory movement of the roll shaft and its adjuncts. Consequently the motion of the cross-head is not restricted in any way by the construction described, and by carrying the oil retainer or guard upward it forms an inner wall for the lubricant chamber made by the outer coupling member, the effective depth of such chamber being substantially equal to the depth of the outer cylindrical wall of the part 11 of the said outer member of the coupling. That is, oil can be introduced thereinto until its level is just below the top of the retainer 33, immersing in the oil the suspension members 14, 27 and a large portion of the segments 17 and the trunnions, and lower portion of the cross-head. The segments 17 of the crosshead will alternately dip into the oil during the operation of the device.

Referring to Fig. 2, it will be seen that there is an annular, elongated space or chamber between the exterior of the retainer 33 and the surrounding portions of the cross-head and suspension members 14, 27, and this chamber or space is brought into free, direct and permanent communication with the interior of the inclosing mem-

ber of the coupling by one or more holes 36, see dotted lines Fig. 2, in the cross-head, just above the seat 25. Preferably I make two such holes, diametrically opposite each other. Now when the chamber formed by the lower part of the outer coupling member is filled with oil, and the mill is at rest, the oil will flow inward through the apertures 36 and into the space surrounding the retainer 33, the level of the oil within the recessed part of the cross-head and outside of it then being the same. When the mill is set in operation the motion of the inclosed cross-head and its adjuncts will of course 15 agitate the lubricant and all portions of the mechanism within the outer coupling member will be maintained thoroughly lubricated, but the centrifugal force generated by rotation of the coupling will cause the oil 20 immediately surrounding the retainer to flow outward through the apertures 36, down to substantially the level of the latter. The oil remaining in the interior of the recessed part of the cross-head, below such 25 apertures, will, however, be ample to maintain thoroughly lubricated the adjacent parts of the suspension members 14 and 27, as will be obvious, while the said parts will also be lubricated by the oil outside the 30 cross-head. Thus a very complete uniformity of lubrication is secured, together with the capacity for holding and retaining a large quantity of oil. When the mill is stopped the oil outside the cross-head will 35 flow back through the apertures 36 until a common level is established, and as will be manifest there is no escape of oil from the coupling.

While the retention of a large quantity of 40 lubricant within the coupling, with the resulting decrease in the frequency for renewals, and greater uniformity of lubrication, are the principal objects attained by my invention it is also to be observed that the exclusion of dust and grit from the contained 45 lubricant is an important feature.

Various changes or modifications in details of construction and arrangement may 50 be made by those skilled in the art without departing from the spirit and scope of my invention as set forth in the claims hereunto annexed.

Having fully described my invention, what I claim as new and desire to secure by 55 Letters Patent is:

1. The combination, with a universal coupling including a closed member having a cylindrical outer wall and a central bottom opening and rotated positively about a fixed 60 vertical axis, an inner tubular wall surrounding the opening, forming with the outer wall a deep annular oil chamber, and a rocking cross-head inclosed by and mounted in said member and having a concentric, downwardly open recess, of a shaft 65

attached rigidly to the cross-head and depending therefrom through and co-axial with the recess, the inner wall of the closed member of the coupling surrounding the shaft and entering the recess in the cross-head, and means to sustain vertically the said coupling, the recess of the cross-head being in continuous communication with the closed member of the coupling above said coupling-sustaining means. 70

2. The combination, with a universal coupling including an outer member having a central opening in its bottom, a cylindrical outer wall, and a frusto-conical inner wall surrounding the opening, and a cross-head 80 mounted to rock in and inclosed by said member, said cross-head having a co-axial frusto-conical and downwardly open recess entered by the said inner wall and in free communication laterally with the outer 85 member of the coupling, of a shaft rigidly attached to the cross-head and depending therethrough, the shaft passing through the inner wall of the said coupling member, and an overhead, vertically sustained driving 90 shaft, rigidly secured to and rotating in unison with the outer coupling member, the inner and outer walls of the latter forming a deep annular oil chamber in which the cross-head rocks, the oil flowing outward 95 from the recessed portion of the cross-head by centrifugal action when the mill is in operation.

3. The combination, with a closed driving member rotatable about a fixed vertical axis 100 a pulley attached thereto, and a cross-head mounted to rock in and inclosed by the driving member and having a downwardly open, central recessed portion, of a shaft rigidly attached to and suspended from the cross-head co-axial with and extended through the recess, an interior tubular retaining wall on the driving member extended upward around the shaft into the recessed portion of the cross-head, to retain lubricant in and 105 increase the effective depth of the driving member while permitting free rocking movement of the cross-head and shaft, and means to sustain vertically the driving member. 110

4. The combination of a suspended driven shaft, a rocking coupling member to which said shaft is attached and from which it is suspended, said member having a central, downwardly flared recess open at its lower 115 end and surrounding the shaft, and in free and continuous communication laterally with the outer coupling member, a closed outer coupling member in which the rocking member is inclosed and by which it is 120 sustained, said outer member having a central opening in its bottom for the passage of the shaft, a tubular, tapered retainer fixed on the outer member concentric with the opening therein and extended upward 125 130

around the shaft into the recess of the rock-ing member, to retain lubricant in and in-crease the effective depth of the outer mem-ber, and a vertically supported driving shaft 5 rigidly connected with the latter.

5. The combination, with an overhead driving shaft, and a suspended gyratory shaft, of a universal coupling between them including an outer member having an annu-10 lar co-axial bearing and a fixedly attached frusto-conical oil-retainer upwardly extend-ed through the bearing, and a crosshead mounted to rock in the outer member and to which the suspended shaft is rigidly at-tached, said cross-head having a frusto-15 conical recess co-axial with the shaft and into which the oil-retainer extends, and a centrally open suspension member inter-posed between the annular bearing and the 20 cross-head and interlocked detachably with the latter, the oil-retainer passing upward through the said suspension member, the cross-head having a lateral aperture connect-ing the recess thereof at all times with the 25 outer coupling member below the top of the oil-retainer and above said annular bearing.

6. The combination, with an overhead, vertically sustained shaft, and a suspended 30 gyratory shaft, of a universal coupling con-nnecting them, said coupling including an in-closing member rigidly attached to the over-head shaft and having a central bottom opening and a surrounding tubular exten-sion depending therefrom, an internal annular seat in said extension, and a rocking 35 cross-head mounted in the inclosing mem-ber and to which the suspended shaft is rigidly attached, the cross-head having a 40 central, downwardly flared and open recess through which said shaft passes, combined with a frusto-conical retainer having an annular base flange fitting oil tight in said annular seat and passing upward around the 45 suspended shaft into the recess of the cross-head, said retainer increasing the effective depth of the inclosing member of the cou-50 pling to form an oil chamber, and a driving pulley rigidly connected with said member of the coupling and concentric therewith.

7. In a device of the class described, in

combination a rotatable member and a cross head supported therein to rotate therewith but capable of a rocking movement relative to said rotatable member, said cross head 55 having a co-axial frusto-conical recess open at its lower end and said rotatable member having a part projecting into said frusto-conical recess.

8. In a device of the class described in 60 combination a rotatable driving element, a cross head having trunnions and provided with a co-axial downwardly open recess in its lower part, said trunnions being con-nected with said rotatable driving member 65 to permit movement in the plane of the axis of said driving member but preventing other movement relative thereto, the wall of the recess of said cross head being apertured lat-erally to establish connection between the 70 recess and the exterior of the cross head.

9. Mechanism for supporting a depend-ing shaft comprising, a shaft, a rocking crosshead secured to the shaft and having a circular bottom recess, and a supporting 75 member for the crosshead having a central opening through which the shaft extends and having an annular oil chamber the in-ner wall of which projects into the recess of the crosshead the recess being larger than 80 the said inner wall to permit a rocking movement whereby the parts of the cross head may dip into the oil in the annular oil chamber.

10. A universal joint comprising a rota-table driving member having an oil chamber and a central bottom opening, a shaft ex-tending through said opening, a crosshead 85 secured to the shaft and connected to rock in the driving member but rotate therewith and a bearing supporting the crosshead and mounted in the oil reservoir of the driving member whereby the supporting bearing 90 may be thereby lubricated while the oil is prevented from escaping onto the shaft. 95

In testimony whereof, I have signed my name to this specification, in the presence of two subscribing witnesses.
